UNITED STATES PATENT OFFICE

WALTER A. THUM, OF ST. LOUIS, MISSOURI

SHOE-HEEL-SETTING DEVICE

Application filed January 30, 1928. Serial No. 250,467.

This invention relates to a certain new and useful improvement in shoe-machinery and has particular reference to a tool or device for setting the heels during the hardening of 5 the adhesive usually employed in binding the wood heel to the shoe.

In the manufacture of a boot or shoe, a last is provided over which the shoe is built. The heel is then mounted on the shoe with 10 suitable adhesive, and the finishing operations are then applied. The heel is today set on the shoe by means of a clamp of such construction that, so far as I am aware, it is necessary that the heel and shoe with the last 15 in it remain in the clamp until the adhesive has hardened, whereupon the clamp may be removed. As at present employed, these clamps prevent any further operations on the shoe so long as they remain thereon, as they 20 are too large and heavy to handle in passing through the machines used in the finishing of the shoe. Hence operations on the shoe must be suspended for a certain time and until the adhesive has hardened, thus tying up a considerable amount of capital in partially completed shoes and greatly increasing the time 25 factor required in the manufacture of a shoe.

My invention has hence for one of its objects the provision of means whereby the heel 30 may be set on the shoe while the adhesive is hardening, and yet at the same time permit the shoe to be passed successively through the operations of trimming and burnishing the sole and the other subsequent operations 35 without removing the last from the shoe and without interfering with or retarding the passage of the shoe through the machines associated with such subsequent operations. By such means, I expedite the manufacture 40 of the shoe, lessen the production time required per shoe, and avoid tying up capital in partially finished shoes pending the hardening of the adhesive, all of which objects are now unattainable in the present state of the 45 art, so far as I am aware.

My invention has for a further object the provision of means of the type and for the purposes stated which may be inexpensively and economically manufactured, durable and 50 sturdy in structure, conveniently usable, and

efficient in the performance of its intended functions.

I accomplish all such objects by the provision of a clamping means for firmly and tightly pressing the heel to the shoe (the last 55 being in the shoe) and then securely holding the parts together by means of a heel-set comprising a shackle associated with a latch, the heel-set being relatively small in dimension for convenient handling when passing 60 through the machines employed in completing the manufacture of the shoe.

And with the above and other objects in view, my invention resides in the novel features of form, construction, combination, and arrangement of parts hereinafter described and pointed out in the claims.

In the accompanying drawings,

Figure 1 is a view, partly in side elevation and partly in section, of a heel-set and clamping means of my invention;

Figure 2 is an end view of the parts illustrated in Figure 1, as seen by the operator of the machine, showing in connection therewith a shoe with its last and heel firmly 75 pressed together and securely held by the heel-set;

Figure 2^a is an enlarged detail section taken approximately on the line 2^a—2^a, Figure 1;

Figure 3 is an enlarged sectional view 80 taken approximately along the line 3—3, Figure 1;

Figure 4 is a detail side view of the heel-set shown in Figure 1;

Figure 5 is a detail end view of the heel-set 85 of Figure 4;

Figure 6 is an enlarged front elevational view of a modified form of heel-set, embodying my invention;

Figure 7 is an end view of the heel-set of 90 Figure 6; and

Figure 8 is a sectional view taken approximately along the line 8—8, Figure 6.

Referring now more in detail and by reference characters to the drawings, my new heel-set comprises a shackle A which includes an inverted substantially U-shaped member 10 of suitable dimensions for accommodating or embracing the usual boot or shoe B, as shown in Figure 2. Preferably, the mem-

55

60

65

70

100

ber 10 has the shape in elevation best seen in Figure 4; however, for accommodating a greater variation in height of heels, this member, as at 10^a, may have the modified form and contour in side and end elevation as seen in Figures 6 and 7. I may here state that otherwise than in shape or form, the member 10^a and its associate parts are similar in function and operation to the preferred form of such member 10 and its associate parts illustrated in the remaining figures of the drawing, and hence a description of one will equally apply to the other.

Disposed transversely of member 10, is a cross-member or plate 11 provided at its opposite ends with enlargements 11^a suitably bored to fit the legs of member 10, whereby the member or plate 11 is disposed for slideable movement relatively to the member 10. Upon their opposed inner faces, the plate enlargements 11^a are suitably slotted, as at 11^b, to accommodate, and permit impinging engagement with the legs of members 10 by, the opposed outer ends of aligning latch-members 12 mounted flatwise for slideable movement upon the under face of plate 11, each latch-member or plate 12 being formed with its outer end recessed, as at 13, complementary to one of the legs of the member 10 and with its inner end provided with inclined faces, as at 14, formed complementary to a conical shoulder or circular wedge-element 15 threaded into the plate 11 for movement cooperatively with the latch-plates 12. Thus, when the wedge-element 15 is screwed into the plate 11, the latch-plates 12 will be oppositely moved or shifted outwardly so as to impingingly engage the respective legs of the member 10 and thereby rigidly secure the members 10 and 11 together. Preferably, the free ends of the legs of the member 10 are provided with shoulders 16 to prevent the plate 11 and its associate parts sliding off the member 10 on disengagement therewith of the latch-members 12.

The shoe assembly comprises a last 19 inserted in the shoe B, upon which latter a heel 20 is mounted and adapted for securement by suitable adhesive. As is usual, the last 19 is provided upon its upper face and at its heel portion with a recess 21 and adjacent its toe portion with a projecting portion or shank 22. Preferably, the plate or member 11 of the heel-set is provided upon its upper face with a last-engaging pad 23, preferably corrugated or roughened upon its upper face to prevent twisting while the operations are being performed on the shoe.

As more fully later appearing, my heel-set 20 may be employed with any suitable form of clamping machine. Preferably, however, I prefer to employ a form of construction as illustrated in Figures 1 and 2, wherein I show a clamping element or frame C comprising a bed-plate 24 rigidly supported by suitable

standards 25. Fixed to and upstanding from the bed-plate 24, is a vertically disposed inverted substantially L-shaped member 26, mounted upon the laterally projecting leg 26^a of which, for limited vertical movement, is a drop-head D comprising a block 27 formed longitudinally on its under face with a groove, as at 28, for accommodating and engagement with the upper portion or bight, 10^b, of the U-shaped member 10. As best seen in Figure 2^a, the block D is provided upon its upper face with a sleeve 29, disposed for slideable endwise movement relatively to an inverted cup 30 fixed in the leg 26^a of the member 26. Abutting at its head 31 against the outer face of the end-wall of cup 30 and threaded at its lower end into the block 27, is a follower 32, and coiled about the follower 32 and abutting at one end against the block 27 and its other end against the inner face of the end-wall of cup 30, is a coil-spring 33 for yieldingly exerting constant downward tension or pressure upon the block 27.

Mounted for reciprocal movement upon the bed-plate 24 and disposed in approximate vertical alignment with the drop-head D, is a clamp-head E adapted for actuation by any suitable means, such as, for instance, an air-piston or the like. In the embodiment here shown, however, the clamp-head E is manually operable by means of a foot-lever 34 pivoted, as at 35, to a rigid bracket 36 fixed to a bed-plate or other support 37 and operatively connected by means of a preferably lengthwise adjustable link 38 to a rack 39 disposed vertically for slideable movement in a housing 40 conjoined or otherwise fixed to and upon the under side of the bed-plate 24. Preferably the rack 39 is in the form of a cylindrical member, held from turning movement by means of a set screw 41 seated in the housing 40 and engaging at its inner end in a slot 42 longitudinally provided and properly positioned in the rack 39. The rack 39 operatively engages a gear 43 journalled for rotation in the housing 40 and, in turn, having meshing engagement with a second vertically disposed rack 44 conjoined to or otherwise forming part of the clamp-head E. Preferably the rack 44 is also of cylindrical formation and is likewise held from turning movement by means of a second set screw 45 seated in the housing 40 and engaging at its inner end in a slot 46 longitudinally provided in the rack 44, all as best seen in Figure 1. At its lower or free end, rack 44 is provided with a collar or abutment 47, and interposed on the rack 44 and abutting at one end against the collar 47 and at its other end against the under face of the housing 40, is a coil spring 48 for yieldingly retaining the clamp-head E in, and returning the same to, normal lowered position.

As best seen in Figure 1, the rack 44 pro-

125

130

jects upwardly through the bed-plate 24, and conjoined to or otherwise fixed upon the projecting upper end of the rack 44, is a member 49 which is generally of cup-shape formation, as shown, the member 49 comprising diametrically - opposite vertically - disposed channels or ways 50, disposed in each of which is a coiled or buffer spring 51, disposed, in turn, upon which are ejector plungers 52. Arranged intermediate the channels 50 and adapted for registering with the wedge-member 15 of the shackle A when the latter is disposed upon the head E with the end-lugs of the member 10 engaging the plungers 52, is a wedge-operator F comprising a spring-set handle-socket ratchet-wrench 53 having its shank 54 journalled in a bridge-piece 55 of the member 49, as clearly seen in Figure 1. In the embodiment here shown, the wedge-element 15 of shackle A is provided with a hexagonal head 15^a, which is adapted to be seated in the shank-head 54^a of the wedge-operator F, the head 54^a having a recess formation complementary to the head 15^a of the wedge element 15, but it will be understood that any other form of wedge operator may be employed, such as an ordinary open ended hand wrench, motor, or the like. Coiled on the wrench-shank 54 and abutting at one end against the end wall of member 49 and at its other end against a collar 57 fixed on the wrench-shank 54, is a spring 56 for normally holding the head 54^a yieldingly in engagement with the head 15^a of the wedge-element 15, so that the operator may conveniently actuate and lock the heel-set after the operation of clamping has been performed.

At a suitable location on the shackle-member 11 for last-engagement, is a pin 58 adapted to engagingly fit the aperture 21 in the last 19 to hold the shoe B in proper operating position; and preferably also the head E is provided with an outwardly presented bracket 59 adapted for engaging the last-shank 22 to serve as a support and a guide for the shoe B and its contained last during heel-setting operations.

Thus, it will be seen that I provide a pressing machine for clamping the heel on the shoe, the last being inserted and disposed within the shoe, and a heel-set or holding device for securely holding the parts in proper position during the hardening and setting of the adhesive. As I have before stated, the heel-set may have its member 10 constructed and formed in any convenient shape in order to present the least possible obstruction to the passage of the shoe-assembly through the shoe-working machines. In this regard, I have shown the members 10 and 10^a, which differ slightly in contour, but it will be understood that I do not limit myself to the specific types of shackle members here shown. Wherever conditions allow, I prefer to use the form of shackle seen in Figures 6 and 7,

this form of shackle being cheaper to manufacture and also having a wider range of usefulness in working with different sizes and makes of shoes and shoe heels.

In use and operation, we will assume first that the member 11 is free to slidably move upon the member 10 and is disposed loosely upon the shoulders 16 at the free ends of the shackle-member 10. The heel-set A is mounted in the clamping machine by inserting the bight 10^b of the shackle-member 10 in the groove 28 of block 27 of head D, the head D being then pushed upwardly yieldingly against the tension of spring 33 so as to permit the ends of the shackle-member 10 to be inserted into the channels 50 and upon the ejector-plungers 52 of the head E. As so disposed, the enlargements 11^a of plate 11 rest upon the shouldered upper end of the cup 49 with the head 15^a of the wedge-element 15 seated in the recessed head 54^a of the wedge operator F. Thus the heel-set is supported and held firmly between the spring seated plungers 52 and the head D. The shoe assembly comprising the last 19, the shoe B mounted on the last, and the heel 20 mounted on the shoe with a suitable interposed adhesive, are now inverted and disposed heelwise within the confines of the shackle member 10 and engaged by the pin 58 and supported and guided by the bracket 59.

The parts being in the position described, the operator depresses the foot lever 34, thereby, through the racks and gearing described, causing the clamp-head E to move upwardly. In such upward movement of the clamp-head E, the shackle A and the inserted shoe B are shifted upwardly until the block 27 of head D yieldingly abuts against the leg 26^a of the member 26, as seen in Figure 2. As the lever 34 is further depressed and head E continued to be shifted upwardly, the cross-member or plate 11 of the shackle A will now be shifted upwardly and the shoe-assembly tightly compressed between the member 11 and the bight 10^b of the shackle A, the member 11 at its pad 23 engaging the outer, and now downwardly presented, face of the last 19 and the shoe-heel 20 engaging at its outer lift firmly against the bight 10^b of the shackle-member 10. The wedge operator F is now actuated to shift the latch-members 12 into engagement with the legs of the member 10, whereby the shoe-assembly and shackle A are securely and firmly held together. On pressure upon the lever 34 being removed, the head E yieldingly moves downwardly to normal position under the tension of spring 48, when the shoe-assembly and shackle A may as a unit be removed from the machine and as a unit conveniently handled and passed through the subsequent or finishing shoe operations. In removing the shoe-assembly, the same is simply lifted up so as to disengage the legs of the shackle-member

10 from the clamping-head E and the last 19 from the bracket 59, whereupon the whole 5 may be withdrawn from the machine and another heel-set inserted therein, and the operations as described again performed. It will be readily seen that the heel-set may be applied to the shoe-assembly in a very short time, and that the heel-set, when applied to the shoe-assembly, takes up very little room 10 and interposes no obstructions that would prevent the passage of the shoe through the finishing machines. I may add that, in disengaging the heel-set from the shoe, the screw-member 15 is suitably loosened, when 15 the latch-members 12 may be easily shifted out of impinging engagement with member 10, and plate 11 then shifted downwardly, permitting ready removal of the shoe.

While I have herein described a certain 20 specific method of constructing and assembling the elements of my invention, it is to be understood that changes in the form, construction, arrangement, and combination of the several parts of my new heel-set and 25 clamping machine may be made and substituted for those herein shown and described without departing from the nature and spirit of my invention as defined in the appended claims.

Having thus described my invention, what 30 I claim and desire to secure by Letters Patent is:

1. A heel-set including an approximately U-shaped body-member adapted to embrace 35 the shoe-assembly, in combination with a second member shiftable relatively to the body-member for co-operative engagement with the shoe-assembly, and means adapted for engagement with the legs of the body-member 40 for retaining the second member in shifted position in setting the heel to the shoe.

2. A heel-set including an approximately U-shaped body-member adapted to embrace the shoe-assembly, in combination with a 45 plate disposed transversely, and having engagement for shiftable movement with the legs, of the body-member, said plate being shiftable relatively to the body-member for engagement with the shoe assembly, and 50 means carried by said plate adapted for engagement with the legs of the body-member for retaining the plate in shifted position in setting the heel to the shoe.

3. A heel-set including an approximately U-shaped body-member adapted to embrace the shoe-assembly, in combination with a 55 plate disposed transversely, and having engagement for shiftable movement with the 60 legs, of the body-member, said plate being shiftable relatively to the body-member for engagement with the shoe-assembly, and means including opposed latch-members carried by the plate for engagement with the 65 legs of the body-member for retaining the

plate in shifted position in setting the heel to the shoe.

4. A heel-set including an approximately U-shaped body-member adapted to embrace the shoe-assembly, in combination with a 70 plate disposed transversely, and having engagement for shiftable movement with the legs, of the body-member, said plate being shiftable relatively to the body-member for engagement with the shoe-assembly, and means for retaining the plate in shifted position in setting the heel to the shoe, said means including a pair of opposed latch-members 75 disposed in relation to the plate for shiftable movement, and a wedge-member having engagement with the plate for shifting the latch-members to engage the legs of the body-member.

5. A heel-set including an approximately U-shaped body-member adapted to embrace the shoe-assembly, in combination with a 80 plate disposed transversely of the body-member for co-operative engagement with the shoe-assembly, apertured enlargements on the plate fitting for plate-shifting movement 85 on the legs of the body-member, said enlargements being transversely slotted, and means for retaining the plate in shifted position in setting the heel to the shoe, said means including a pair of opposed latch-members 90 disposed in relation to the plate for shiftable movement and fitting at their outer end in the slots of said enlargements, and a wedge-member 95 having threaded engagement with the plate and adapted for actuating engagement with said latch-members at their inner end to shift the latch-members to impingly engage at their outer end with the legs of the body-member.

6. In combination with a heel-set including a shackle comprising a first member adapted to embrace the shoe-assembly and a second member shiftable upon the body-member for co-operative engagement with the shoe-assembly, of means for yieldingly shifting the second member into engagement with the shoe-assembly.

7. In combination with a heel-set including a shackle comprising a first member adapted to embrace the shoe-assembly and a second member shiftable upon the body-member for co-operative engagement with the shoe-assembly, of a block adapted for engagement with one end of the first member, a movable clamp-head for accommodating the opposite end of the first member in opposed relation to the block, the head being adapted for engagement with said second member, and means for actuating the head to shift said second member into engagement with the shoe-assembly.

8. In combination with a heel-set including a shackle comprising a U-shaped member adapted to embrace the shoe-assembly and a plate transversely disposed to said

member and fitting upon the legs thereof for shiftable movement for co-operative engagement with the shoe-assembly, of a block adapted for engagement with the bight of the U-shaped member, a movable clamp-head channeled to receive and accommodate the legs of the U-shaped member and adapted to engage said plate, and means for actuating the head to shift said plate into engagement with the shoe-assembly.

9. In combination with a heel-set including a shackle comprising a U-shaped member adapted to embrace the shoe-assembly, a plate transversely disposed to said member and fitting upon the legs thereof for shiftable movement for co-operative engagement with the shoe-assembly, and means including a wedge-member carried by the plate for retaining the same in shifted position in engagement with the shoe-assembly, of a block adapted for engagement with the bight of the U-shaped member, a movable clamp-head channeled to receive and accommodate the legs of the U-shaped member and adapted to engage the plate, means for actuating the clamp-head to shift the plate into engagement with the shoe-assembly, and means including a wrench-member carried by the clamp-head adapted for actuating engagement with said wedge-member.

In testimony whereof I affix my signature.

WALTER A. THUM.
